UNITED STATES PATENT OFFICE

2,097,693

COMBINED DIE AND PATTERN

Fred L. Foster, Lynn, Mass.

Application October 16, 1934, Serial No. 748,464

1 Claim. (Cl. 164—29)

The invention relates to improvements in a combined die and pattern for cutting irregular configurations of articles, such as shoe parts, shirts, gloves, etc., of which the following is a specification:

The invention consists of a novel means of supporting a pattern in a die by rigidly securing a reinforcing member having suitable supporting lugs formed integral therewith to the inner surface of the die which alternately support both sides of the pattern to make a substantial and durable structure.

The object of the invention is to provide a supporting means on the inner surface of a die for a pattern of any configuration to make a unit structure which is easy to manufacture at a maximum durability and a minimum cost.

Referring to the figures:

Fig. 1 is a plan view of the die and pattern showing the support.

Fig. 2 is a side elevation of the die shown in a cutting position in a checking machine.

Fig. 3 is a part vertical section of the die and pattern showing the supporting member.

Fig. 4 is a plan view of the same.

Fig. 5 is a side elevation of the supporting member.

Fig. 6 is a plan view of the same.

Fig. 7 is a side elevation of the supporting member before the supporting lugs are bent into position.

Fig. 8 is a fragmentary plan view of the die and pattern with the lugs bent into position.

Referring to the drawing which illustrate the improvements in supports for a combined pattern and double-edged die used for cutting material such as leather, cloth or fiber in a checking machine to withstand the maximum cutting strains with a lightweight die. The die and pattern are indicated by the numerals 10 and 11 respectively. The die is made of thin strip material and preferably with two cutting edges 12 and 13 to permit left and right hand articles to be formed with the same die. The die operates against the stock 14 which can be of any suitable material.

The stock is placed on the cutting block 15 and the die is placed on the stock, as shown in Fig. 2 of the drawing, preparatory to the cutting operation. To force the die 11 through the stock 14 a reciprocating movement of the operating head 16 in its downward movement operates against the die forcing it through the stock, and the opposite upward movement away from the die allows the next operation to take place.

The die is made of a thin material which can be formed and manipulated around the pattern

by machine or hand practice in contradistinction to the heavy forged dies now in use.

Because the die is made of thin material, the operating head 16 and the cutting block 15 are made of soft material so the die can sink into it and cushion the impact so the edges 12 and 13 will not be injured. The die is removed from the block by a special spring device to prevent them from sticking in the soft material.

The embodiment of the invention consists of a double-edge die made of strip material which can be readily formed to the contour of the pattern 11 of any configuration: that is, any form can be made and the die can be placed around it due to the flexible nature of the material. The novelty resides in providing a suitable support for the pattern inside the die to withstand the working strains and reinforce the die when in use.

The reinforcing member 17 is also made of strip material which can be formed around the pattern and secured to the inner surface of the die 10. Formed in the strip material are the supporting members 18 and 19. These supporting members are bent over at right angles to the inner surface of the die and reinforcing member, of which they are a part, at right angles and alternately extend over and under the pattern and all the members are welded together to make a unit construction for supporting a pattern to a die.

The reinforcing strip before it is secured to a die, is machined to form a series of two V-shaped slots on both edges of the reinforcing strip in alternate positions leaving the supporting members 18 and 19 free to be bent at right angles to serve as the supporting member for the pattern, one set on the top side of the pattern, and one set on the lower side of the pattern.

In operation and construction the die 10 is made of flexible strip material having two edges 12 and 13 and is known as a double-edge die which can be used for right and left articles.

The pattern is made in any configuration and after the supports 18 and 19 are formed in the reinforcing member 17 it is bent around the pattern and welded. Following this operation, the die is now ready for operation.

What I claim as new and desire to secure by Letters Patent of the United States is:

In a double edge die in combination with a pattern of the shoe type, a supporting member secured to the inside surface of the die, lugs formed in the supporting member which alternately support both sides of the pattern.

FRED L. FOSTER.
